UNITED STATES PATENT OFFICE.

LISENA ALICE FENNER, OF JERSEY CITY, NEW JERSEY, EXECUTRIX OF
JOHN H. FENNER, DECEASED.

ROPE OR CABLE GUIDE.

SPECIFICATION forming part of Letters Patent No. 658,908, dated October 2, 1900.

Application filed May 12, 1900. Serial No. 16,509. (No model.)

To all whom it may concern:

Be it known that JOHN H. FENNER, late a citizen of the United States, and a resident of Jersey City, New Jersey, did invent certain new and useful Improvements in Rope or Cable Guides, of which the following is a specification.

This invention relates to improvements in rope or cable guides designed for use on dredgers and similar situations where the rope from the hoisting-engine or windlass passes over a swinging boom.

The object of the invention is to provide a simple and durable construction where the maximum degree of movement shall be allowed to the boom with a minimum degree of friction on the hoisting rope or cable.

To this end the invention comprises a base, a frame rotatably mounted thereon, and guide-pulleys carried thereby at right angles to each other.

The invention further includes the details of construction as hereinafter described, and particularly pointed out in the claims.

25 The invention is illustrated in the accompanying drawings, in which—

Figure 1 is a plan view. Fig. 2 is a side elevation. Fig. 3 is a detail view.

In the drawings numeral 3 indicates a base-plate, which is preferably in the shape of an open ring and is provided with lugs 3^a, having openings by which it may be bolted to the deck of a scow or analogous place.

4 designates the base portion of a rotary frame which is provided with an angular flange 4^a, which rests in a rabbet in the base and is held therein by a removable ring 3^b, but is allowed free rotary movement therein. Two upright posts 5 are carried by this rotary plate 4, and on these are journaled horizontal-disposed guide-pulleys 6, which are arranged directly in line with each other and each of which is provided with a rope-groove 6^a and a retaining-flange 6^b. A yoke 7 connects the tops of the posts. The posts are preferably made removable from the rotary ring by having their lower ends seated in socket-pieces 4^c and held in place by suitable pins 4^d. The yoke, it will be observed, is also removable by taking out the pins at the top

of the posts. A supplemental plate 7' is bolted to the rotary plate on one side of the posts, and upon this plate are mounted two vertical webs 8, which have rearwardly-extending portions 8^a, rigidly secured to the 55 yoke above referred to. Between these webs is journaled a pulley 9 upon a horizontal axis, the lower edge of this pulley coming approximately in line with the center of the horizontally-arranged pulleys before referred to. 60 Lugs or projections 10 extend outwardly from the vertical webs, preferably at about the inclination of a hoisting-boom, and in these lugs are journaled pulleys 11 upon inclined axes 11^a. These rollers, it will be observed, 65 are elongated cylinders, and thus permit a movement of a rope or cable longitudinally between them, but prevent any lateral motion. In order to prevent the rope slipping down from between the rollers when the cable 70 is slack, a horizontally-disposed roller or pulley 12 is provided.

Having thus described this invention, what is claimed is—

1. In combination with a base or support, 75 the frame rotatably carried thereby, and the guide-pulleys carried thereby having their axes arranged in different planes, substantially as described.

2. In combination with a base, a plate rotatably carried thereby, horizontally-arranged opposing pulleys carried by said plate, and a vertically-disposed guide-pulley having its lower edge arranged in line with the space between said opposing pulleys, substantially 85 as described.

3. In combination with a base, a plate rotatably carried thereby, vertical posts on said rotary plate, opposing pulleys carried by said posts, a yoke connecting said posts at their 90 upper ends, vertically-arranged webs carried by said rotary plate and yoke, and a pulley journaled between said webs, substantially as described.

4. In combination with a base, a rotary 95 plate thereon, posts carried by said plate, opposing guide-pulleys carried by said posts, a yoke connecting the upper ends of said posts, vertical webs carried by said rotary plate and yoke, a guide-pulley journaled between said 100

webs adjacent to the horizontal pulleys and cylindrical pulleys journaled in ears at the outer edges of the webs, substantially as described.

- 5 5. In combination with a base, a rotary plate thereon, posts carried by said plate, opposing guide-pulleys carried by said posts, a yoke connecting the upper ends of said posts, vertical webs supported by said plate and 10 yoke, a guide-pulley journaled between said webs, inclined parallel cylindrical rollers journaled at the outer edges of said plates, and a roller journaled at the lower ends of said cylindrical rollers upon a horizontal axis, 15 substantially as described.
6. In combination with a base having an open center with an annular rabbet, a rotary plate having its edge seated in said rabbet, a retaining-ring for holding said rotary plate 20 in said rabbet, and a plurality of angularly-

disposed guide-pulleys carried by said plate, substantially as described.

7. In combination with a suitable base or support, a rotary plate carried thereby, removable posts carried by said plate, opposing pulleys journaled on said posts, a yoke 25 removably carried by the upper ends of said posts, vertical webs connected to said yoke and also removably connected to said rotary plate, and guide-pulleys carried by said webs, 30 substantially as described.

In testimony whereof I have hereunto signed my name to this specification in the presence of two subscribing witnesses.

LISENA ALICE FENNER,
Executrix of the estate of John H. Fenner.
